UNITED STATES PATENT OFFICE.

LOUIS BLESSING, OF JACKSON, MICHIGAN.

STAMP-CANCELING MACHINE.

1,053,350.

Specification of Letters Patent. Patented Feb. 18, 1913.

Application filed August 12, 1911. Serial No. 643,676.

To all whom it may concern:

Be it known that I, LOUIS BLESSING, a citizen of the United States of America, residing at Jackson, in the county of Jackson and State of Michigan, have invented certain new and useful Improvements in Stamp-Canceling Machines, of which the following is a specification, reference being had therein to the accompanying drawings.

10 This invention relates to letter canceling machines and more especially to an arrangement thereof whereby little power is required to operate the machine which is positive and simple of construction.

15 The invention consists in the matters hereinafter set forth and more particularly pointed out in the appended claims.

In the drawings, Figure 1 is a plan view with parts removed of a letter canceling machine that embodies features of the invention; Fig. 2 is a view in transverse section through the machine; Fig. 3 is a view in longitudinal section through the machine; Fig. 4 is a view in end elevation, partially in 25 section of a part of the machine; and Fig. 5 is a view in end elevation of part of a drum showing a modification of the latter.

Referring to the drawings, a hollow stationary shaft 1 is connected to an exhaust pipe 2 at one end and an air pipe 3 at the other. The shaft is mounted in a table 28 and a drum is journaled thereon to turn through a suitable opening in the table. Preferably the drum is made in two sections one of which 4 is provided with suction ports 5 and carries cancel stamps 6 adjacent the ports, the stamps being removably secured as by insertion in dove-tail or undercut slots. At the point where the ports pass 30 the table top a pair of cut off plates 7 are supported by means of a yoke 8 made fast to the shaft 1, the latter having a plurality of openings 9 within the drum. A pair of idler pulleys 10 adjacent the drum carry an 35 endless belt 11 of suitable material which extends around the periphery of the drum between the cut-off plates 7 below the surface of the table so as to seal the ports 5 as they swing below the table. An inking 40 roll 12 is placed adjacent the drum to contact with the stamps thereon as the latter pass up through the table. A cleaning roll 13 is in running contact with the belt 11 where the latter has just left the drum.

50 55 A countershaft 14 journaled in suitable brackets 19 on the table carries a presser

roll 15 to force letters held by the suction of the ports against the stamps. The countershaft may be driven by any suitable means, as for example, a main pulley 16 and a belt 17 passing over an upper idler 18 and under a drive pulley 20 on the counter shaft. A guide block 21 is placed on the table adjacent the drum and over the inking roll 12. A discharge nozzle 22 is adapted to direct a blast of air from any source of supply against letters placed on edge and moved along the guide block toward the drum, the nozzle being so disposed that the air blast separates each letter of the stack as it in 55 turn approaches the drum, from the preceding letter so that it is readily picked up by the suction through the port of the drum and carried around under the presser roll. A stripper plate 23 removes the letters from 60 the drum as the ports pass the outer cut-out plate down through the table. The drum itself is driven by a pulley 24 or the like. The outer cut out belt 11 may, if desired, be omitted and the inner cut off plates 7 be 65 extended to form a continuous segmental plate. Such construction is shown in Fig. 5, a segment 26 being mounted on the shaft within the drum on an arm 27 and sealing the ports 5 during their passage below the 70 table. In neither construction is the stoppage of the ports complete, the plates and belt or the segment making only a partial closure, so that there is some leakage but this is off-set by the fact that the cut-offs do not 75 frictionally engage the drum and so the power required to operate the device as a 80 whole is very slight.

The construction of the drum in two sections admits of its ready inspection while 85 the running parts are few in number and when once adjusted the machine does its work without further attention.

Obviously, changes in the details of construction may be made without departing 90 from the spirit of the invention and I do not wish to limit myself to any particular form or arrangement of parts.

What I claim is:—

1. A letter canceling machine comprising 105 a table, a hollow shaft secured across an opening therein and provided with lateral apertures, a closed drum rotatable on the shaft around the apertures provided with peripheral suction ports, stamping means on 110 the drum periphery adjacent the ports, means for pressing letters held by the suction of

the ports on the drum against the stamping means, and means for shutting off the ports during the time they are passing below the plane of the table.

5. 2. A letter canceling machine comprising a table, a hollow shaft with lateral openings journaled across an opening in the table, a closed drum rotatable on the shaft around the opening provided with suction ports through its periphery, stamping means on the periphery adjacent the ports, means for pressing letters held by the suction of the ports on the periphery against the stamps, and means for shutting off the ports during 10 the time they are passing below the plane of the table.

3. A letter canceling machine comprising a table, a hollow shaft with lateral openings secured across an opening in the table, a closed drum rotatable on the shaft around the apertures and provided with suction ports in its periphery, means secured on the shaft within the drum for shutting off the ports during the time they are passing below the plane of the table, stamping means on the drum periphery adjacent the ports, means for pressing letters held by the suction of the ports on the periphery against the stamping means, and operating mechanism for the drum.

4. A letter canceling machine comprising a table, a hollow shaft with lateral openings secured across an opening in the table, a closed drum rotatable on the shaft around the openings, a segmental cut off plate mounted on the shaft within the drum and adapted to shut off the ports while they are passing below the plane of the table, and means for stamping letters as they are held 40 against the periphery of the drum by the suction of the ports.

5. A letter canceling machine comprising a table, a hollow shaft with lateral openings secured across an opening in the table, a closed drum rotatable on the shaft around the openings thereof provided with suction ports through its periphery, a segmental cut off plate mounted on the shaft within the drum for shutting off the ports while they are passing below the plane of the table, pneumatic means for forcing letters on the table into the range of action of the suction ports, and stamping means for impressing letters held against the drum periphery by 50 the suction of the ports.

6. A letter canceling machine comprising a table, a hollow shaft with lateral openings secured across an opening in the table, a

closed drum rotatable on the shaft around the openings thereof provided with suction ports through its periphery, a segmental cut off plate mounted on the shaft within the drum for shutting off the ports while they are passing below the plane of the table, pneumatic means for forcing letters on the table into the range of action of the suction ports, stamping means on the drum periphery adjacent the suction ports, a pressing roll for forcing letters held on the drum by the suction of the ports against the stamping means, and means for rotating the drum and presser roll.

7. A letter canceling machine comprising a table, a hollow shaft with lateral openings secured across an opening in the table, a closed drum rotatable on the shaft around the openings provided with peripheral suction ports, stamping plates detachably secured on the periphery adjacent the ports, a segmental cut-off plate secured on the shaft in substantially sliding contact with the inner peripheral face of the drum for shutting off the ports while they are passing below the plane of the table, a pressing roll in substantially rolling contact with the drum for forcing letters held against the periphery by the suction of the ports against the stamping plate, and means for operating the drum and roll.

8. A letter canceling machine comprising a table, a hollow shaft with lateral openings secured across an opening in the table, a closed drum rotatable on the shaft around the openings provided with peripheral suction ports, stamping plates detachably secured on the periphery adjacent the ports, a segmental cut off plate secured on the shaft in substantially sliding contact with the inner peripheral face of the drum for shutting off the ports while they are passing below the plane of the table, a pressing roll in substantially rolling contact with the drum for forcing letters held against the periphery by the suction of the ports against the stamping plate, pneumatic means on the table for advancing letters on the table into the range of action of the suction ports, an inking roll for the stamping plates, and means for rotating the drum and roll.

In testimony whereof I affix my signature in presence of two witnesses.

LOUIS BLESSING.
